UNITED STATES PATENT OFFICE.

IDA M. FIELD, OF NEW YORK, N. Y.

DESIGN FOR A BELT-HOOK.

SPECIFICATION forming part of Design No. 28,723, dated May 31, 1898.

Application filed March 26, 1898. Serial No. 675,192. Term of patent 7 years.

To all whom it may concern:

Be it known that I, IDA M. FIELD, a citizen of the United States, residing at 255 West Fifty-fifth street, in the city, county, and State of New York, have invented and produced a new and original Design for Belt-Hooks, of which the following is a specification, reference being had to the accompanying drawings, forming part thereof, in which—

Figure 1 is a front elevation of a belt-hook, showing my new design. Fig. 2 is a vertical sectional view, and Fig. 3 is a plan or top view.

This invention relates to a design for belt-hooks of that type which are used for holding the waistband of a skirt in engagement with a belt, the design consisting in the shape of the inner or back plate, the hook, and the ornament attached to the hook.

As shown in the drawings, the material or leading feature of my design consists of the belt-hook provided on its face with the ornament A in the shape of a fleur-de-lis, which is embellished on its face, as shown, the back thereof being flat or plain. Adjacent to the lower portion of the ornament A are parallel bars, between which are beads. The face of the fleur-de-lis is ornamented by a scroll, and

the inner side edges are beaded. The plate B is curved longitudinally, so that the side adjacent to the ornament A will be convex, and it is provided adjacent to its ends with holes or apertures b. From the center of the plate B extends a hook C, which is of sufficient length to reach below the lower edge of the plate.

The essential features of my design embrace the plate B, with the apertures therein, a hook C, which projects in front of the plate and extends both above and below the horizontal edges of the plate, and an ornament or fleur-de-lis which is attached to the outer face of the hook.

Having thus described my invention, what I claim as new, and desire to secure by Letters Patent, is—

The design for a belt-hook herein shown and described.

In testimony whereof I have hereunto set my hand in presence of two subscribing witnesses.

IDA M. FIELD.
